UNITED STATES PATENT OFFICE.

CHARLES H. MOORE, OF YONKERS, NEW YORK.

WATER-CLOSET CISTERN.

SPECIFICATION forming part of Letters Patent No. 274,214, dated March 20, 1883.

Application filed July 20, 1881. (No model.)

To all whom it may concern:

Be it known that I, CHAS. H. MOORE, a citizen of the United States, residing at Yonkers, in the county of Westchester and State of New York, have invented a new and useful Water-Closet Cistern, of which the following is a specification.

My object is to furnish a flushing-cistern for water-closets from which a given amount of water only can be drawn at each discharge of the closet, and to provide a retainer in the service-box to supply the closet with a desired quantity of water after the termination of the first flushing and closing of the water-closet-discharge valve. It is likewise my object to furnish a simple means of supplying the cistern.

In the accompanying drawings, making a part of this specification, Figure 1 represents a central vertical section. Fig. 2 represents a top view.

A shows the main tank, and A° a measuring-compartment formed by a vertical partition, K, and supplied through a port, B°, in the vertical partition by preference.

G shows a service-box having a valve, C, operating on the discharge-port N. Said valve C is provided with a stand-pipe, M, which extends far enough up into the service-box to retain sufficient water in the service-box to furnish a closet with the desired quantity of water when the outlet-valve is shut. Upon the lever H being depressed the valve C closes the port N, and the valve D opens and admits water to the service-box G, and from thence through the stand-pipe M to the closet. Upon the valve D being opened the mechanism is arranged to close the valve E of the port B°. This prevents any admission of water from the main cistern A, so that when the closet is held open the compartment A° empties, while the water in the main cistern A is retained. Water is also retained in the service-box up to the mouth of the stand-pipe M. Upon releasing the lever H the valve C is opened and the contents of the service-box delivered to the closet, where it is again held until the next action of the closet.

The cistern can be made of wood and lined with suitable metal; but in this case it is shown made in one piece having a dividing-

partition, J, to form the service-box G. This partition J is a separate piece, having the seat of valve D and the guide placed in it, and it is afterward placed in the bottom of compartment A° and calked with lead around the margin to keep it firm and form a water-tight joint. When this plate or partition J is used in a wooden cistern lined with metal it is placed in as shown and soldered to the metal lining. 55

Heretofore iron cistern service-boxes have been exposed to the action of water, the result of which is an accumulation of rust on the inner walls, and as water leaves the cistern suddenly it becomes agitated in the service-box and discolored with rust, and in this state it is delivered to the delf-bowl of the water-closet, which finally becomes discolored. To provide against this I line the service-box with a metal that will not rust. This lining F is fastened to the plate J in 60 a manner to prevent water coming in contact with the iron box. The port B° on the vertical partition K is provided with a valve-seat and a bar extending across it with a hole in the center for the spindle of valve E to operate in 65 to guide said valve E to its seat. The valve E is also provided with a loop, into which the part H° of the lever H enters to open and close the said valve E.

H represents an angle-lever, the part H° extending down into the cistern, where it is intended to open and close the valve placed on the port B° of the partition K. The said lever would also operate a valve if placed on the opposite side of the partition from where the 75 valve E is shown.

I represents a support stationed in the cistern, to which the lever H is secured to operate the discharge-valves.

The supply-valve of the cistern is made to 80 close with the pressure. A screw-thread is made in neck L of chamber S, and a corresponding thread on spindle U, which, upon being turned in, forces the valve a into the chamber P, permitting water to flow into the cistern. Upon turning the spindle the opposite 90 way the valve a is drawn tight against the valve-seat formed on the end of chamber S, that screws into the chamber P. This chamber P is provided with a screw-nut, e, which, when 95 removed, leaves an opening large enough in said chamber P to pass the valve a through it

to renew the washer. The chamber S can be cast in one piece with chamber P if desirable, but I prefer making it separate, to screw on after the chamber P is secured to the supply pipe. The packing-nut R is screwed on the neck L to prevent leakage. The outlet-port T of the chamber S has a thread cut on it, into which a solder coupling is screwed. It is intended to solder a tube to said coupling to conduct water noiselessly to the bottom of cistern. The valve is operated by a weighty float, O, secured on the end of lever f. To provide a cheap float of sufficient weight, I make it of enameled earthenware or wood, and have a hole made through to allow the lever f to pass through the center, where it is made firm by the use of a nut. B shows the overflow of the cistern.

Having described my invention, what I claim as new, and desire to secure by Letters Patent, is—

1. In a water-closet cistern having a compartment formed by a vertical partition and supplied from the main cistern through a port in said partition, the service-box G, having a means provided in it for retaining a reserve of water until after the termination of the first flushing and closing of the inlet-valve D of the service-box G and the outlet-valve of the closet, and then delivering it to the closet, substantially as described.

2. In a water-closet cistern having a compartment divided from the main cistern by a horizontal plate in the bottom of cistern, said compartment being arranged to be empty at all times when the closet is not in use, the valve C, having a tube, M, attached to it, substantially as shown, and a way through said tube M for the discharge of water to the closet when the valve C is closed, in combination with the discharge-pipe N, overflow-pipe B, and inlet-valve D.

3. The combination, with the service-box G and inlet-valve D, of the horizontal plate J, having a margin of thicker proportion than the plate, and a calked lead joint, g, made between the margin and sides of the cistern, substantially as shown.

4. In a water-closet cistern, the lever H, having the part H^o cast or secured to it in a rigid manner and extending down into the cistern

to a valve operating on a port in a vertical partition.

5. In a water-closet cistern having a vertical partition with a port in it near the bottom, a valve-seat fitted in the port of the partition, and having a guide across the center, and a valve-spindle operating in said guide, substantially as shown.

6. The combination, with a water-supply valve, of a float with a vitreous surface, provided with a passage, x, through its center, and a lever, f, extending through said passage, as and for the purpose set forth.

7. In a water-supply cock, the combination, with the inlet-chamber P, valve a, operating in inlet-chamber P, and closing in the direction with the pressure-valve seat p in chamber P, outlet-chamber S, neck L, having a spiral groove cut in the inner walls, and spindle U, having a spiral thread cut on it corresponding with and operating in grooves in the neck L, of the packing-nut R, fitted on the spindle U and screwed on the end of neck L, inclosing the grooves on the spindle and in the neck L, with in said neck L, substantially as shown.

8. In a water-supply cock, the combination, with the inlet-chamber P, inlet-port U^o of the chamber P, valve a, operating in chamber P, and closing in the direction with the pressure-valve seat p in chamber P, outlet-chamber, neck L, having a spiral groove in it, and spindle U, of the nut e, screwed in the end of chamber P, the lever f, and float O, substantially as shown.

9. In a water-cock, the combination, with the inlet-chamber P, valve a, operating in inlet-chamber P, and closing in the direction with the flow of water against the seat p, and outlet-chamber S, of the neck L, having a spiral thread cut in the inner wall, but not extending through said wall, and the spindle U, having a spiral thread cut in it to correspond with and operate in the thread cut in the neck L, substantially as shown, and for the purpose of opening and closing the valve a, as set forth.

C. H. MOORE.
